HARRIE A. BALLARD, OF BOSTON, MASSACHUSETTS, ASSIGNOR TO THE BOYLSTON MANUFACTURING COMPANY, OF SOUTH BOSTON, MASSACHUSETTS, A CORPORATION OF NEW JERSEY.

LOCK-STITCH SHOE-SEWING MACHINE..

1,142,391.

Specification of Letters Patent. Patented June 8, 1915.

Application filed June 16, 1909. Serial No. 502,493.

To all whom it may concern:

Be it known that I, HARRIE A. BALLARD, of Boston, in the county of Suffolk and State of Massachusetts, have invented certain new and useful Improvements in Lock-Stitch Shoe-Sewing Machines, of which the following is a specification.

This invention relates to shoe sewing machines of the lock stitch type. In machines of this type, it is customary to employ a shuttle which revolves continuously in one direction located above the needle in a shuttle race which is open at the bottom for the purpose of admitting and discharging the loop of needle thread which passes over the shuttle. By providing sufficient open space in the shuttle race for the passage of the needle thread, the shuttle is deprived of a supporting structure where it is most needed and considerable difficulty is experienced in supporting the shuttle throughout its rotary movement because the periphery of the shuttle is by necessity cut away for the purpose of receiving the loop of needle thread. When the shuttle and shuttle race are cut away, as explained, the shuttle, if not otherwise supported, is liable to unduly wear the race so that after comparatively little usage the shuttle becomes so loosely confined in the race that it drops slightly once during each revolution. The objection resulting from so cutting away the shuttle and the shuttle race has in some machines been remedied to a certain extent by providing additional exterior supports for the shuttle. Exterior supports are objectionable because the point of contact and consequent friction are so far remote from the axis of rotation that motion of the shuttle is unduly resisted.

One of the chief objects of the present invention is to provide an internal support for the shuttle in addition to the support afforded by the shuttle race. By "internal" is meant a point within the circumference of the shuttle as distinguished from an external support.

Another important feature of the present invention relates to the presserfoot which is employed for holding the work upon a stationary or fixed work table. In all shoe sewing machines especially those which are operated at high speed, the work is subjected

to more or less jerking by reason of the rapidity with which it is fed. It is of the utmost importance that the work should be so firmly held between the stages of its step-by-step movement that there shall be no possibility of dislodging it so as to displace the awl hole from alinement with the needle. On the other hand the work should be sufficiently relieved for the purpose of feeding it between the periods when the presserfoot is locked. That portion of the machine to which this feature of the invention relates comprises a movable presserfoot subjected to spring pressure which causes it to hold the work upon the work table, and locking means which, when actuated to lock the presserfoot, not only performs the duty of locking but also imparts to the presserfoot a slight additional movement toward the work table, thereby clenching the work against all possibility of displacement.

In stitching the forepart of the shoe sole, it is sometimes desirable to employ comparatively short stitches and to place them relatively close to the edge of the work, whereas in stitching along the shank portions of the sole it is desirable to employ comparatively long stitches and to place them farther in from the edge of the work. To those skilled in the art of stitching shoe soles it is well known that the object of placing the shank stitches farther in from the edge of the sole is to leave abundant material between the shank stitches and the edge for the final edge trimming operation in which the shank is trimmed to a greater extent than the forepart.

A further object of the present invention is to provide means adapted to be manually actuated while the machine is in operation for varying the length of the stitches and at the same time varying the position of the stitches relatively to the edge of the work. For this purpose a movable work guide is provided together with actuating mechanism connected to a manually operative handle, the changing of which effects a change in the extent of movement imparted to the work-feeding means. The work guide and work-feeding means and their adjusting devices are so related that, when the handle is moved so as to increase the length of the

stitches, the work guide is retracted so as to provide more space between the stitches and the edge of the work.

Still another feature of the present invention is embodied in a spring takeup device for the locking thread of which the supply is contained within the shuttle.

The foregoing features as well as additional features are hereinafter described in detail, illustrated upon the accompanying drawings and particularly set forth in the appended claims.

Of the accompanying drawings which illustrate one form in which the invention may be embodied, Figure 1 is a front elevation of a complete sewing machine with power transmitting mechanism. Fig. 2 is a front elevation of detached mechanism including the stitch-forming mechanism and work-feeding mechanism in their correct relation to each other. Fig. 3 is a side elevation as seen from the right of Fig. 2. Fig. 4 is a front elevation of a portion of the work-feeding mechanism. Fig. 5 is a side elevation and partial section as seen from the right of the feeding mechanism, the work-gage mechanism, the presserfoot mechanism, and thread-locking mechanism. Fig. 6 is a side elevation as seen from the left of the presserfoot mechanism, thread-locking mechanism and takeup mechanism. Figs. 7 and 8 are elevations as seen from the left of fragments of the presserfoot locking mechanism in different positions. Fig. 9 is a detail of the stitch-forming mechanism. Fig. 10 is a section on line 10-10 of Fig. 9. Fig. 11 is another detail showing an advanced stage of forming a stitch. Fig. 12 is a side elevation as seen from the left of detached mechanism including the takeup mechanism, looper mechanism, thread-measuring mechanism, and work guide mechanism. Fig. 13 is a side elevation as seen from the left of gearing forming a part of the looper mechanism. Fig. 14 is a top plan view of said gearing. Figs. 15 and 16 are top plan views of the looper in different positions. Fig. 17 is a top plan view of the work table and work guide. Fig. 18 is a front elevation of the shuttle race and portions of the needle and awl mechanism. Fig. 19 is a section on line 19-19 of Fig. 18. Figs. 20 and 21 are respectively a front elevation and right side elevation of a cam which actuates the interior shuttle support. Fig. 22 is a front elevation of the shuttle alone. Fig. 23 is a section on line 23-23 of Fig. 22. Fig. 24 is an elevation of the open side of a bobbin case adapted to be inserted in the shuttle. Fig. 25 is a section on line 25-25 of Fig. 24. Fig. 26 is a perpendicular section of a bobbin adapted to fit within the bobbin case. Fig. 27 is an elevation of the member which supports the shuttle internally. Figs. 28 and 29 are perpendicular sections of the

shuttle, shuttle driver and shuttle support in different positions. Fig. 30 is a front elevation of the shuttle race and shuttle mechanism in the act of forming a stitch. Fig. 31 is a top plan view of the looper mechanism. Fig. 32 is a top plan view of the needle and awl mechanism together with fragments of the supporting frame and feed carriage. Fig. 33 is a left side elevation of the mechanism shown by Fig. 32. Fig. 34 is a section on line 34-34 of Fig. 33. Fig. 35 is a side elevation of the needle mechanism. Fig. 36 is a side elevation as seen from the left of the awl mechanism and a fragment of the feed carriage supporting the same. Fig. 37 is a section on line 37-37 of Fig. 32. Fig. 38 is a perpendicular longitudinal section of stop mechanism for controlling the stopping of the machine. Fig. 39 is a top plan view of the stop mechanism. Figs. 40 and 41 are elevations of centrifugal governing mechanism in the two positions occupied respectively when the machine is at rest and in operation. Fig. 42 is an elevation of the cushioning spring which causes the stopping of the prime power shaft.

The same reference characters indicate the same parts wherever they occur.

Referring now to Fig. 1, there is illustrated a form of shoe sewing machine of the lock stitch type which illustrates a convenient manner in which the several features hereinafter explained may be applied for the purpose of carrying out the present invention. It should be understood, however, that the invention is not limited to this precise form of machine but that several mechanisms herein illustrated may well be modified to meet certain requirements without departing from the spirit and scope of the invention. On Fig. 1 is shown a head or frame 10 on which are installed the several operative mechanisms and which is shown as mounted on a base or standard 11. Power-transmitting mechanism is shown and includes a countershaft 12 provided with the usual tight and loose pulleys 13, 14 and with coöperative clutch members 15 and 16 of which one may be splined and of which the other may be loosely mounted. According to the form illustrated the member 15 is loosely mounted and the member 16 is splined. The member 15 is grooved to receive a belt 17 which passes over a pulley 18 affixed upon the prime power shaft 20 which is journaled in bearings 21 upon the head 10. Mechanism for controlling the application of power is hereinafter explained.

The head 10 includes the lower half 19 of a divided cylindrical casing of which the upper half is indicated at 22. The casing, comprising the portions 19 and 22, surrounds the portion of the shaft 20 between the bearings 21 and forms a chamber for inclosing the several cams and gears by which

power is distributed to the several mechanisms. The casing being divided on a line level with the axis of the power shaft, provides a receptacle for containing an abundance of lubricating oil in which the several cams and gears may be immersed.

Needle mechanism.—The needle employed, which is indicated at 23, is of the hooked oscillatory type and is illustrated in detail by Figs. 32 and 35 inclusive. The needle is mounted on a carrier 24 to which it is clamped by a bolt and clamping plate 25. The carrier is formed with a cylindrical boss 26, which forms its bearing, about the axis of which it is adapted to oscillate. The boss 26 is surrounded by two members 27 which constitute a split bearing and which are inserted in an aperture formed in a projecting bracket 28 formed on the head 10. The outer end of the boss 26 is formed with an external flange 29 which confines the two members of the split bearing against endwise movement. The bearing so assembled may be secured in the bracket 28 as hereinafter explained.

Awl mechanism.—30 indicates an awl which is likewise of the oscillatory type and which is clamped upon a carrier 31 by means of a bolt 32 and clamping plate 32'. The needle carrier, as hereinafter explained, receives oscillatory motion but is positively held against axial motion while the awl carrier receives oscillatory as well as axial motion. By reason of so actuating the awl and needle, the awl is adapted to penetrate the work at a relatively distant point to feed the work toward the needle and to recede from the work so as to leave the awl hole in alignment with the needle, and while the needle is in the work, the awl is adapted to be returned to its relative distant position so that upon subsequent oscillation it is adapted to enter the work at a fresh point. The awl carrier and needle carrier are coupled by a central pin and socket telescoping connection whereby they are positively maintained in axial alignment with each other, and they are furthermore coupled by eccentric pin and socket telescoping connection whereby they are caused to oscillate in unison. In this form oscillatory motion is imparted directly to the awl carrier and motion is transmitted through the eccentric connection to the needle carrier.

55 The awl carrier is mounted in an arm 33 formed upon a feed carriage 34 by means of a split bushing or bearing 35 similar to the bearing 27 of the needle carrier, see Fig. 37. For this purpose the awl carrier is formed 60 with a cylindrical boss 36 at the outer end of which is an external flange 37. The two portions of the split bearing are assembled upon the boss 36 between the flange 37 and the carrier, and the parts thus assembled 65 are inserted in an aperture 33* formed in the

outer end of the feed carriage arm as shown by Fig. 34. One of the parts of the split bearing is securely locked in the arm 33 by a screw or pin 38 such as that indicated in Fig. 37. The same form of locking device 70 is employed as shown by Fig. 34 for fastening the split bearing of the needle carrier hereinbefore described. For this purpose the said part of the split bearing is formed with a notch in its periphery adapted to receive the locking pin. The bearing member thus engaged by the locking pin is held by the pin against axial movement, the interior boss is held against axial movement by the part of the bearing which is pinned 80 and by the flanges at the ends of the boss, and the complementary part of the bearing is therefore held against axial movement by reason of its confinement between the said flanges of the boss. This form of bearing 85 obviates the use of bolts or screw studs usually employed at the ends of the needle and awl bearings and provides a neat and strong mounting which requires but a comparatively small space.

By reference to Fig. 34 it may be seen that the two carriers 24 and 31 are located between their supporting bearings. The inner side of the carrier 31 is formed with a central cylindrical pin or stud 39 which extends into a socket 40 formed in the inner end of the boss 26 of the needle carrier. The feed carriage 34 is movable in parallelism with the axis of the needle and awl carriers and the said carriers therefore have a central 95 pin and socket connection with each other.

The inner side of the needle carrier 24, see Fig. 35, is formed with an eccentric pin or stud 41 which extends into a socket 42, see Fig. 36, formed in the inner face of the awl carrier 31. By this means the two carriers have eccentric pin and socket connection with each other by reason of which oscillatory movement of one is transmitted to the other. The awl carrier 31 is formed 100 with a series of spur teeth 43 which form a gear segment by which it may be oscillated.

Fig. 3 illustrates actuating mechanism for oscillating the awl carrier, said mechanism including an arm 44 pivotally mounted upon the shaft 45 at the rear of the machine and provided with teeth 46 forming a gear segment in intermeshed relation with the teeth 43. The arm 44 is pivotally connected at 47 with the actuator 48 which has the form 115 of an eccentric rod and which embraces an eccentric 49 affixed upon the power shaft 20.

The means for mounting the awl carrier may be reinforced as shown by Fig. 37, for the purpose of more firmly supporting the 125 awl carrier. Said means includes cooperative interlocking segmental rings 50 and 51 of which one may be affixed to the feed carriage arm 33 and the other to the awl carrier. As shown by Fig. 37, the inner ring 130

50 is affixed to the arm 33 by means such as rivets 52, and the ring 51 is likewise affixed to the awl carrier. The inner ring 50 is formed with an exterior flange 53 which 5 overlaps and confines an interior flange 54 formed on the ring 51. The ring 51 is furthermore confined by a concentric flange 55 formed on the arm 33 of the feed carriage. By this arrangement of interlocking flanges 10 the awl carrier is abundantly supported so as to enable it to withstand the lateral strain imposed upon it by the feeding of the work. The bolt 32 is braced by the ear 33' of the arm 33.

15 *Needle guide or support.*—The needle is provided with a movable guide or support 56 which is mounted upon an oscillatory carrier 57. The carrier 57 as shown by Figs. 32 and 34, is mounted upon the exterior of 20 the split bearing 27 between the needle carrier and the bracket 28. The carrier 57 is adapted to oscillate about the needle axis independently of the needle carrier and is actuated so as to cause the guide or support 25 56 to follow the needle in approaching the work and to recede with the needle when the latter is withdrawn from the work. For this purpose is provided an actuator shown 30 in Figs. 3, 32 and 35, said actuator having the form of a link 58. One end of the actuator is pivotally connected to the swinging arm 44 as indicated at 59. The other end of the link 58 is formed with a cylindrical knob 60 which occupies a cylindrical recess 35 61 formed in the inner face of the carrier 57, see Fig. 33.

40 *Work-feeding mechanism.*—The feed carriage 34 upon which the awl is mounted is arranged in guides 34' on the head 10, see Fig. 1. It is reciprocated by a lever 62 pivoted at 63 and having at one end a roll 64, see Fig. 5, co-operating with the cam 65 formed in a cam disk 66 affixed upon the shaft 20. The other end of the lever 62 is 45 formed with a segmental slot 67 which is occupied by a pivoted block 68 carried at the free end of an arm 69. The arm 69 is pivotally mounted at 70 upon the feed carriage 34 and is adjustably clamped to a handle 71 by which it may be moved about its pivot so as to move the block 68 toward or from the fulcrum 63. The feed lever 62 receives oscillation of a uniform length from its cam and it imparts reciprocatory motion 50 of variable length to the feed carriage by reason of the adjustable connection therewith through the movable block 68. The curvature of the slot 67 is such as to be concentric with relation to the pivot 70 when 55 the feed carriage is at the left hand extreme of its movement, in which position the awl is in transverse alignment with the needle. The limit of movement of the awl away from alignment with the needle is varied by 60 swinging the handle 71 and the arm 69

about the pivot 70. This adjustable capacity of the feed carriage connections effect a variation in the length of the stitches by reason of varying the length of the steps in the intermittent movement imparted to 70 the work and this means of adjustment is further employed for the purpose of gaging the distance at which the stitches are formed relatively to the edge of the work.

75 *Work guide or gage.*—Referring now to Figs. 2, 9, 12 and 17, 72 indicates a stationary work rest or table. The table is formed with an elongated aperture 73 through which the needle and awl pass in entering and leaving the work. The work is held 80 upon the upper surface of the table by a presserfoot 74 hereinafter described in detail and illustrated best by Fig. 9. 75 is a work guide or gage which is adapted to be engaged by the edge of the work for the 85 purpose of maintaining the work in correct position relatively to the needle and awl. The work guide is movable from front to rear for the purpose of permitting adjustment for varying the distance of the stitches 90 from the edge of the work. As shown by Figs. 5 and 12, the work guide is formed upon one end of a sliding member which may be arranged in suitable guides, not shown, on the frame 10. The other end of 95 said sliding member is pivotally connected to one end of a link 76 of which the other end is pivotally connected to the free end of an arm 77 affixed upon one end of a rock shaft 78. The rock shaft is mounted on the 100 head 10 in suitable bearings, not shown, and has at its other end an adjustable arm 79. The arm 79 is connected with the handle 71 by various members forming an adjustable universal connection by which movement of 105 the handle about the pivot 70 causes movement of the work guide toward or from the line of the needle. Said universal connection comprises a member 80 pivotally mounted in a boss 81 formed upon the rear 110 side of the handle 71. The boss 81 extends through an aperture 82 formed in the feed carriage. The member 80 is pivotally connected with one end of a link 83 the other end of which is a socket adapted to receive 115 the spherical end 84 of a stud 85 carried by the arm 79. By means of this form of connection, the work guide is retracted from the line of the needle when the handle 71 is moved so as to increase the length of the 120 stitches, and is moved toward the line of the needle when the handle is moved to diminish the length of the stitches. The position of the work guide is not affected by the reciprocatory movement of the feed carriage 125 34 and such movement of the carriage is made possible without disturbing the arm 79 by reason of providing the ball and socket joint described at 84. The relative degree of movement of the work guide may 130

be increased or diminished by adjusting the stud 85 toward or from the rock shaft 78. For this purpose the arm 79 is formed with a segmental slot 86 in which the stud 85 is adjustably clamped.

Presserfoot.—The presserfoot 74 is fixed at one end of a presserfoot lever 87 and is adapted to engage the upper surface of the work and hold the work upon the work table 72. The lever 87 is pivoted in the head 10 at 88 and is formed with spur teeth 89 which form a gear segment concentric to the axis of the pivot 88. The segment 89 has intermeshed relation with the teeth of a pinion 90 loosely mounted on the shaft 45. The pinion is affixed to a drum 91 also loosely mounted on the shaft and containing a coiled spring 92 of which one end is affixed to the hub of the drum and of which the other end is attached to a fixture 93 on the head 10, see Fig. 6. The tension of the spring is applied to the pinion 90 in such a way as to cause the presserfoot to normally clamp the work against the work table, and at no time is the tension of the spring relieved by automatic means. For the purpose of raising the presserfoot from the table in order to facilitate the insertion and removal of the work, the lever 87 may be manually retracted by means of a handle 94. During the greater part of the time in which the machine is in operation, the presserfoot lever is positively locked against retraction by means hereinafter described and is unlocked twice during each cycle of movements at one time for the purpose of permitting feeding of the work, and at the other time when the machine is in the position which it occupies when finally brought to a state of rest in order that it may be ready for manual retraction by means of the lever 94.

The periphery of the drum 91 is provided with ratchet teeth 95 which are adapted to be engaged by a plurality of co-operative teeth formed upon a pawl 96 carried by a lever 97. The pawl is pivotally mounted in the lever as at 98 and the lever is pivotally mounted upon a fulcrum 99. The lever 97 is provided with a roll 100 which is adapted to co-operate with a cam on the shaft 20. The cam for this purpose may be formed with a groove or path for the reception of the roll 100 or may be formed with peripheral indentations as shown by Fig. 6 in which the cam is indicated at 101 and the indentations at 102 and 103. When the latter form of cam is employed a spring 104 is provided for moving the lever in one direction so as to maintain the roll 100 in contact with the cam.

The upper end of the pawl 96 is engaged by a spring 105 which exerts its tension to maintain that end of the pawl in contact with the stop 106 carried by the lever 97. When the shaft 20 is at its initial position,

the indentation 103 of the cam 101 permits the spring 104 to retract the lever 97 so as to disengage the pawl 96 from the ratchet teeth 95. When the pawl is thus retracted, the presserfoot lever is free to be manually retracted against the tension of the spring 92 for the purpose of permitting insertion and removal of the work. When the lever 97 is actuated against the tension of the spring 104, the ratchet teeth 95 are engaged first by the foremost tooth 107 of the pawl, and continued movement of the lever 97 causes the succeeding teeth of the pawl to enter between the teeth 95 thus rocking the pawl about its pivot 98 against the tension of the spring 105. The final movement of the lever 97 during which the pawl is rocked as described, causes a slight rotary movement to be imparted to the drum 91 which movement is transmitted to the presserfoot lever through the pinion 90 and causes the presserfoot to more firmly clamp the work upon the work table. In this way the continuous yielding pressure of the presserfoot upon the work is reinforced by a slight additional positive pressure and the presserfoot is securely locked against retraction so long as the pawl remains in engagement with the teeth 95. The indentation 102 of the cam 101 permits retraction of the lever 97 and consequent releasing of the drum 91 immediately prior to feeding movement of the feed carriage 34, thus relieving the work of the additional pressure previously imposed upon it. After the feeding movement of the carriage, the lever 97 is again actuated so as to clamp the work with additional pressure and to lock it against retraction during the remainder of the cycle of movements until the shaft 20 once more arrives at its initial position.

Clamping means for needle thread.—The needle thread, see Figs. 6, 9 and 30, may be drawn from any convenient source of supply, preferably at the rear of the machine. The thread, which is indicated at *a*, is preferably waxed and is drawn from a suitable tension roll *b* shown in Fig. 6. After passing over the tension roll, the thread passes through a clamping device, a takeup device, and a looper all of which are herein-after described. The clamping device is mounted upon the presserfoot lever 87 and is bodily movable. It comprises a clamping roll 108 and a lever 109 pivoted at 110 to the lever 87. The thread passes between the roll 108 and a block 111 affixed to the lever 109, and is normally clamped by spring tension exerted by a spring 112 of which one end is connected to the lever 87 and the other end to an arm of the lever 109. The clamping action of the block is continuous except as herein-after explained. The clamping lever 109 is provided with a projection or a roll 113 which is adapted to be engaged by a

curved arm 114 forming a part of a lever 115. The lever 115 is mounted upon the shaft 45 and has at its free end a roll 116 which occupies a cam groove 117 formed in the cam disk 66, see also Fig. 5. The arm 114 is retracted from the roll 113 during the major portion of the cycle of movements but is actuated twice during each revolution of the shaft 20 for the purpose of retracting the lever 109 and opening the thread clamp. A shoulder 118 in the cam 117 opens the thread clamp when the shaft 20 is at its initial position and a shoulder 119 in said cam opens the thread clamp for the purpose of permitting the shuttle to draw from the supply a quantity of thread *a* as hereinafter explained. The arm 114 is so curved as to be concentric to the pivot 88 of the presserfoot when the thread clamp is open and is thus adapted to maintain the clamp in open position when the presserfoot lever is moved about its pivot.

Takeup mechanism.—The takeup mechanism herein shown for the thread *a* comprises 25 a pair of oscillatory arms 120, 121, see Figs. 6 and 12. Said arms are mounted upon a stud 122 and are actuated simultaneously in opposite directions so as to cause them to move toward and from each other. The arm 30 120 is provided with a bell crank arm 123 which is pivotally connected to one end of a link 124 of which the other end is pivotally connected to an actuating lever 125. The arm 121 is likewise provided with a bell 35 crank arm indicated at 126, said arm being pivotally connected to one end of a link 127, of which the other end is pivotally connected to the lever 125. The lever 125 is loosely mounted upon the shaft 45 and is provided 40 with a cam roll 128 which occupies a cam groove 129 formed in a cam disk 130. The arms 120 and 121 are provided respectively with thread rolls 131 and 132. The thread rolls are so arranged that those of one arm 45 are adapted to enter between those of the other arm in alternate order. The thread passes from the clamping roll 108 over an idle roll 133 mounted upon the presserfoot lever and thence to the series of thread rolls 50 on the takeup arms. When the takeup arms are in closed position the thread is permitted to pass between them in a rectilinear course but when they are open, as indicated on the drawings, they form a series of zigzags in 55 the thread and thus draw down the loose thread from the stitch-forming mechanism. The form of connection between the actuating lever 125 and the link 124 includes a curved slot 134 in which the connecting pivot 60 is clamped. By adjusting the pivot toward or from the fulcrum 45, the lever 125 may be caused to impart more or less movement to the takeup arm 120 and in this way vary the capacity of the takeup mechanism.

Looper mechanism.—The looper, which is 65 illustrated in detail in Figs. 6, 9, 12 and 31, is indicated at 135. It is mounted in one end of a carrier 136 and engages the thread between the takeup mechanism and the work table 72. The carrier 136 is mounted to slide 70 longitudinally in a hanger 137. The hanger is mounted in the head 10 upon a pivot 138 about which it is adapted to oscillate. The other end of the looper carrier is formed with an aperture 139 which is occupied by 75 a crank or wrist pin 140 at the lower end of an upright shaft 141. The shaft 141 is rotated intermittently in one direction so as to cause the looper to move to the two positions indicated by Figs. 15 and 16. The 80 looper moves through a circular path in the opposite direction to the path through which the crank 140 moves, and it is driven first through approximately 120° of a circle and then through the remaining 240° to its 85 initial position. The initial position of the looper is shown by Fig. 16 in which it is in perpendicular alignment with the needle. The first movement imparted to the looper carries it to the position shown by Fig. 15 90 where it remains stationary during feeding of the work, after which the needle is moved downwardly to receive a loop of thread. While the needle is in its lower position, the looper is moved through the second 95 stage from the position shown by Fig. 15 to that shown by Fig. 16 in the direction of the arrow for the purpose of laying a loop of thread upon the barb of the needle. The looper, after arriving at its initial position, 100 remains stationary in alignment with the needle while the needle is retracted through the work.

The means for driving the shaft 141 intermittently in one direction comprises a 105 pair of spiral gears 142 and 143 of which the former is affixed to the upper end of the shaft 141 and of which the latter is affixed to the shaft 20. The gear 143 is formed with two series of teeth indicated 110 at 144 and 145. Both ends of said series are joined by peripheral ribs or flanges 146 and 147. The series 144 of the larger gear is adapted to intermesh with a series of teeth 148 of the smaller gear, while the 115 series of teeth 145 is adapted to intermesh with the series of teeth 149. The series 148 and 149 are separated by grooves or indentations 150 and 151, said grooves being respectively adapted to receive the ribs 146 120 and 147. The looper, as formerly stated, is first moved through a relatively short arc and then through a relatively long arc in describing a circle, and for this reason the several series of co-operative spiral teeth are 125 made of unequal length as indicated by Figs. 13 and 14. The two series 144 and 148 which co-operate move the looper

through a relatively short arc, while the longer series 145 and 149 move the looper through a relatively long arc.

Thread measuring device.—In Figs. 9, 10 and 12, 152 indicates a thread-measuring device which is adapted to engage the needle thread between the looper and the needle for the purpose of drawing the quantity of thread which it subsequently delivers to the needle, while the needle is being retracted through the work. The measuring device is in the form of a rod of which one end is formed as a hook as shown by Fig. 10, and of which the other end is loosely mounted in a stud 153 mounted in the head 10. Between its ends the member 152 is mounted by means of a suitable pivoted connection in one end of an actuating lever 154. The lever is mounted upon a fulcrum indicated at 155 and is provided with a cam roll 156 which co-operates with a cam groove 157 formed in the cam disk 130. The cam actuates the lever 154 so as to reciprocate the member 152 forward and backward as hereinafter explained.

Shuttle mechanism.—The locking thread, which is indicated at α in Fig. 30, is wound about the central core of a bobbin 158 such as that illustrated in Fig. 26. According to this form of the invention the bobbin is rotatively mounted upon a stud 159 arranged in the center of a bobbin case 160. The bobbin case is provided with a tension spring 161 which is arranged to engage the exterior convolutions of thread contained in the bobbin and exert pressure upon the thread toward the core of the bobbin.

The bobbin case is formed with a slot 162 through which the thread α may be drawn off. The bobbin case is adapted to be contained in the chamber 163 formed in the front side of a shuttle 164. The shuttle is formed with a rear wall 165 in which is a central aperture 166 whose function is hereinafter explained. The periphery of the shuttle is formed with a rib or flange 167 which is adapted to fit in a groove 168 formed in a shuttle race comprising separable parts 169 and 169 α . The shuttle race is arranged upon a horizontal axis and is formed with a gap 170 for the purpose of admitting the needle thread α as shown by Fig. 30. The shuttle is also formed with a nose 171 which is adapted to engage a loop of the needle thread and carry it over the bobbin thread. The nose is provided with a flange 167 α which travels in the groove 168 of the race. The periphery of the shuttle is cut away on one side so as to provide a space within the circular portion of the race for the reception of a driver 172, see Fig. 18. The driver is formed on one end of a shaft 172 α which is arranged in suitable bearings in the head 10 of which one is indicated at 173 in Fig. 19. The shaft is 65 driven continuously in one direction indicated by arrows, at a uniform speed, and for this purpose its rear end, see, Fig. 3, is provided with a spiral gear 174 which is driven by a spiral gear 175 on the shaft 20. 70 The driver is so formed as to provide a clear space 176 between it and the rear wall of the shuttle, as indicated by Fig. 29, and it also provides a clear space between it and the periphery of the shuttle as indicated at 75 177. The space thus provided is for the purpose of enabling a loop of needle thread to pass over the shuttle and to become interlocked with the bobbin thread. The shuttle is formed with a shoulder 178 which is 80 adapted to be engaged by the driver and by which rotative movement is imparted to the shuttle. By reason of cutting away both the shuttle and the shuttle race, as shown and explained, the shuttle is not sufficiently 85 supported by the race during a portion of its cycle and it is therefore desirable to otherwise support the shuttle in order to prevent it from sagging or dropping into the gap at the bottom of the race, and thus in time 90 wear away the race and render the shuttle unfit for use. For this reason an auxiliary supporting device 179 is mounted upon the driver by means of a pivot pin 180. The support 179 is adapted to oscillate about 95 the pivot and is formed with a head 181 which is adapted to enter the aperture 166 in the rear wall of the shuttle. When the head 181 occupies said aperture, it is adapted to engage the wall of the aperture and 100 thus confine the shuttle centrally within the race. When the auxiliary support is in engagement with the wall of the aperture, it bridges the space 176 at the rear of the shuttle and would thus form an obstruction 105 to the passage of the needle thread unless retracted. As shown by Figs. 28 and 29, the driver is adapted to guide the needle thread into the space 176 so that the thread cannot become caught on the member 179. 110 A member 182, located within the part 169 α of the shuttle race, retracts the support 179 to enable the needle thread to pass through the space 176 and returns said support to shuttle-engaging position when the needle 115 thread has passed. Said member 182 is in the form of a cap and is affixed to the bearing 173 and provided with an aperture for the driver shaft 172 α . The cap is formed with an end cam 183 and with a peripheral 120 cam 184. The supporting member 179 is formed with faces 185 and 186 which co-operate respectively with the stationary cams 183 and 184. The supporting member in revolving with the driver is projected by 125 the cam 183 and retracted by the cam 184, said cams being so related to each other as to actuate the supporting member positively

in both directions without loss of motion. It is not essential that the portion of the shuttle which is engaged by the supporting member should be the wall of an aperture 5 for it might well be any other form of shoulder occupying an equivalent relation.

According to this invention the bobbin case 160 is provided with a tension device and with a spring takeup for the thread α .
 10 The tension device is in the form of a leaf spring 485 and the takeup device is shown as a spring hook 186. The thread drawn from the bobbin passes first through the slot 162 in the wall of the bobbin case, thence through a groove 187 in the front wall of the case, thence between the tension spring 485 and the front wall of the bobbin case, through the spring hook of the takeup 186, through an aperture 188 extending 15
 20 through a nose 189 on the bobbin case and thence to the work. The nose 189 is engaged by a retaining arm 190 which serves to retain the case in the chamber 163 of the shuttle and it also holds the case against 25
 30 rotation. The arm 190 is pivoted at 191 to ears formed on the shuttle race and is adapted to be engaged and locked by an overlapping bolt 192 pivoted at 193. The free end of the arm 190 is bifurcated as shown by Fig. 3, and is adapted to straddle the nose 189.

Loop opening mechanism.—In Figs. 2, 3 and 30 is illustrated a finger 194 which is adapted to engage a new loop of the needle thread for the purpose of opening the loop for the introduction of the nose of the shuttle. The thread-engaging end of said finger is formed as a hook and the other end is adjustably clamped in one end of a lever 195. The lever is pivotally mounted in the head 10 upon the stud 155 which forms the fulcrum of the thread-measurer-actuating lever 154. The lever 195 is provided with a cam roll 196 which co-operates with a cam groove 197 formed in the cam disk 66. The finger 194 initially occupies its lowermost position in the path of the nose of the shuttle and is raised as the needle approaches its uppermost position. In this 50 way the hook at the end of the finger removes the newly formed loop of thread α from the needle and spreads the bight of the loop as indicated by Fig. 11, so as to provide for the entrance of the nose of the 55 shuttle into the loop.

Stitch-forming operation.—Suitable mechanism hereinafter described is provided for stopping the shaft 20 at a predetermined initial position when the power is discontinued. When the shaft and the various instrumentalities hereinbefore described, occupy their initial positions, the needle and awl are both clear of the work, the presserfoot is unlocked and the thread clamp is held open in order that the work may be

readily inserted or removed by manually retracting the presserfoot against its spring tension. At this time the needle and awl are approximately midway between their two extremes of oscillatory movement, the looper 70 is in perpendicular alinement with the needle, the thread-measuring device is midway between the extremes of its forward movement, the presserfoot is unlocked, as already stated, the loop-opening finger is at its lower 75 position, the take-up arms are separated, the nose of the shuttle is at or near its lowest position, the feed carriage and awl are at the right hand extreme of their range of movement and the clamping device for the 80 needle thread is open. In inserting a piece of work, the presserfoot is manually retracted by means of the handle 94, the work is placed upon the upper surface of the work table in contact with the work guide, and the presserfoot handle is then released whereupon the presserfoot immediately 85 clamps the work upon the table. When a sufficient quantity of the threads α and ω are drawn out and the ends thereof are momentarily held upon the work, the machine is ready to be set in operation. The power-controlling mechanism, hereinafter described, may then be actuated to start the shaft 20. When the shaft is set in motion, 90 the awl which is below the work and the needle which is above the work both rise so that the awl enters the work preparatory to feeding it. The work is immediately clamped with additional force against the work table and the presserfoot lever is locked by means of the pawl 96, as hereinbefore explained, for the purpose of resisting the thrust of the awl in entering the work. Meanwhile the takeup arms 120 and 121 begin to close for the purpose of providing sufficient loose thread for 100 a loop to be placed on the barb of the needle. The thread clamping lever is released so that the tension of the spring 112 may be applied to clamp the thread as hereinbefore described. The thread-measuring hook advances to its forward position and the presserfoot is again unlocked upon the completion of upward movement of the awl. The feed carriage is then moved to the left and the awl, which is initially distant from the line of the needle, is thus moved into alinement with the needle preparatory to downward movement. At the completion of the feeding movement, the presserfoot is again 115 moved slightly toward the work table and locked so as to hold the work firmly during the operation of the stitch-forming instrumentalities. The needle and awl are now oscillated downwardly in alinement with each other and the needle enters the work in the aperture formed by the awl. During the downward movement of the needle the looper is moved from its initial position in alinement with the needle to the forward 120 125 130

position shown by Fig. 15. When the needle reaches its lower position, the takeup arms 120, 121 are completely closed and the thread-measuring hook is at its forward extreme. While the needle dwells momentarily in its lower position, the feed carriage is moved to the right thus moving the awl out of alignment with the needle and into a position where it may enter the work at a fresh point. The thread-measuring hook and the looper then move nearly simultaneously, the former moving to the rear and engaging the thread *a* between the looper and the work table and drawing back a quantity of thread, as indicated by Figs. 9 and 10. Meanwhile the looper moves from the position shown by Fig. 15 to the position shown by Fig. 16, thus laying the loop of thread about the barb of the needle as shown by Fig. 9. The looper then stops in alignment with the needle and the needle begins to rise to pull the newly formed loop through the work.

During the upward movement of the needle, the thread measuring hook moves forward and thus delivers a measured quantity of thread to the needle in order to avoid drawing the thread through the barb thereof. The takeup arms are in the act of closing and the thread clamp is opened and closed before the needle reaches its upper position. The operation thus far described deals with the instrumentalities which are active in performing the necessary operations during the first cycle of movements, and the second cycle and each subsequent cycle brings into play other instrumentalities whose functions are now described in the following explanation of a subsequent cycle.

Assuming that the various instrumentalities after having completed the first cycle of movements, arrive at their respective initial positions, the order of procedure is as follows:—The needle with a loop of thread in its barb and the awl which is in position to penetrate the work at a fresh point continue to rise in unison so that the needle emerges from the upper side of the work and the awl enters the under side of the work immediately thereafter. At this time the takeup arms are in the act of closing, the thread clamp is permitted to close, the presserfoot is locked and the loop-opening hook engages the loop of thread upon the needle and spreads the loop as shown by Fig. 11. Meanwhile the nose of the shuttle, which is moving continuously in a counterclockwise direction, enters into the loop as shown also by Fig. 30 and removes the loop of thread from the hook finger. Leaving the description of the shuttle operation temporarily, the presserfoot is again unlocked and the work is fed by movement of the feed carriage and awl. After the feed-

ing movement the presserfoot is locked and the awl starts to leave the work, and the needle moving in unison therewith, starts to enter the hole vacated by the awl. During the preceding movements the thread clamp is closed and the nose of the shuttle which is now rising continues to draw the loop of thread, thus setting the preceding stitch if in fact there is one. The hooked finger which delivers the loop of thread to the shuttle now moves to its lower position where it remains stationary until a fresh loop of thread is presented to it by the needle. After the shuttle, which is still rising, has set the preceding stitch and before it reaches its highest point, the thread clamp is opened so that continued upward movement of the shuttle may draw in a fresh supply of the thread *a* for the next stitch. As the nose of the shuttle approaches its highest point, the auxiliary shuttle support, which has hitherto been maintained in supporting position in the central aperture of the shuttle, is retracted by the action of the cams 183 and 184 to permit the passage of the needle thread about the rear of the shuttle. When the nose of the shuttle reaches its highest point, the takeup and thread clamp are both closed. The nose of the shuttle now starts to descend on the other side of its perpendicular diametrical line and the takeup starts to open so as to draw down the needle thread and take up the excess caused by downward movement of the nose of the shuttle. At this time the feed carriage and the awl move again to the right and the looper and thread-measuring hook are actuated as hereinbefore described, for the purpose of laying a new loop of thread about the barb of the needle which now occupies its lower position. The nose of the shuttle continues to descend and the takeup continues to open thus drawing down the previous loop of thread so as to draw it out of the path of the shuttle. The thread so drawn is now interlocked with the bobbin thread *a* and the nose of the shuttle is at or near its lowest point and is approaching the hooked loop-opening finger which is now about to remove another loop of thread from the needle. The takeup arms, previously opened for the purpose of drawing down the interlocked loop of needle thread, are now open and the upwardly moving needle is fully supplied with thread both from the takeup and from the thread-measuring device which is moving forward. Continued motion of the several instrumentalities causes them to form successive stitches according to the operation now fully described.

It is apparent on Figs. 22 and 30 that the chamber 163 in the shuttle provided for the reception of the bobbin case is eccentric

with relation to the axis of the shuttle. The bobbin is thus given a circular motion about the axis of the shuttle and the motion thus produced enables the thread α 5 which is firmly held upon the work to draw through the outlet in the bobbin case and through the tension spring 485, the spring takeup 186 and the aperture 188 in the nose of the bobbin case. The result of rotary 10 movement of the bobbin about the axis of the shuttle is to draw the thread out by a succession of impulses. The action of the spring 161 within the bobbin case serves not only as a tension upon the thread but as a 15 friction brake for preventing the bobbin from continuing to turn about the stud 159 as would otherwise be the case on account of the momentum imparted to the bobbin when the bobbin thread is drawn. It is apparent 20 that the yielding tension of the take-up spring 186 serves to hold the thread α in a taut condition between the work and the tension spring 485.

The means hereinbefore mentioned for 25 causing the driving shaft 20 to stop at a predetermined initial position is illustrated by Fig. 1 and Figs. 38 to 42 inclusive. The co-operative clutch members 15 and 16 arranged upon the countershaft 12 at the rear 30 of the machine are adapted to be moved to and from operative relation by a fork or yoke 198 mounted upon a shaft 199. The shaft is provided with a treadle 200 by which it may be oscillated in one direction 35 and the fork 198 is connected to a spring 201 by which the shaft is oscillated in the other direction. The yoke engages a grooved hub 202 with which the clutch member 16 is provided and the spring 201 exerts 40 its tension to normally retract the clutch member to inoperative position. When the treadle 200 is depressed the clutch members are forced together and power is thus applied by means of the belt 17 to the pulley 18 affixed upon the shaft 20. When the treadle 45 is relieved of downward pressure and the clutch members are separated by reason of the spring 201, the driving power is discontinued and the shaft 20 would continue to 50 revolve indefinitely by reason of momentum unless provided with means for arresting its movement. The means herein provided is adapted to permit continued rotation of the shaft 20 until such time as the speed of said 55 shaft is retarded to a predetermined degree, whereupon automatic stopping devices are brought into play for stopping the shaft at a predetermined position.

The form of mechanism herein shown for 60 stopping the shaft comprises co-operative stop members of which one is relatively stationary and of which the other is rotatively carried by the shaft 20. The stationary stop member is shown as a shoulder 203 formed 65 in the outer end of one of the shaft bearings

21. The movable stop member see Fig. 42, is indicated at 204 and is here shown as a hook or finger formed at one end of a relatively heavy helical spring 205. The spring is arranged upon the shaft 20 so as to loosely 70 surround the same and is adapted to be projected toward and retracted from the bearing 21. The other end of the spring is connected as indicated at 206 in Fig. 38 to a sleeve 207 splined or otherwise secured upon 75 the shaft 20 so as to be rotated thereby and to be longitudinally movable thereon. A helical spring 208 surrounds the sleeve 207 and is compressed between a flange 209 on the sleeve and the hub of the pulley 18 and 80 exerts its force to normally project the movable stop member 204 into engagement with the stationary stop member 203. The flange 209 is formed with an ear 210 which is adapted to be engaged by a retaining arm 85 211 formed upon a lever 212. The lever is pivotally mounted upon a stud 213 which is carried by the pulley 18 and is provided at its opposite end with a weight 214 by which the arm 211 is moved into operative 90 correlation with the ear 210 when the weight is subjected to centrifugal force. The weighted end of the lever is connected to a spring 215 carried in a casing 216 with which the pulley is provided for inclosing 95 the several members described. The tension of the spring 215 tends to hold the weight 214 toward the axis of the shaft 20 as indicated by Fig. 40. In this position the retaining arm 211 is retracted from the ear 100 210, but when the shaft and pulley are rotated at a sufficient speed to cause the weighted lever to assume the position shown by Fig. 41, the retaining arm 211 is moved to such a position as to be adapted to be engaged by the ear 210 and thus retain the movable stop member in retracted position. For the purpose of placing the several parts in the position shown by Fig. 1, the machine is provided with a lever for retracting the 110 movable stop member. Said lever is indicated at 217 in Figs. 1 and 38, and is pivoted at 218 to any suitable fixture such as a portion of the head 10. One end of the lever is formed as a fork and is provided with knobs 115 219 which straddle the movable stop member and which are adapted to abut against the outer end of the sleeve 207. The lever is connected by a link or chain 220 with the treadle 200 by means of which it is adapted to be actuated for the purpose of retracting the movable stop member.

When the clutch members 15 and 16 are moved into operative engagement by depressing the treadle 200, the shaft 20 is immediately set in motion and the movable stop member is retracted so that the ear 210 is moved beyond the inner face of the retaining arm 211. As the speed of the shaft 20 approaches the maximum point, the 130

weight of the lever 212 causes the lever to move to the position shown by Fig. 41 in which position it remains so long as the speed of the shaft is kept above a certain 5 predetermined degree.

When the treadle 200 is released, the clutch members 15 and 16 are immediately uncoupled and the driving power is thus discontinued, but so long as the speed of the 10 shaft 20 is in excess of said predetermined speed, the weighted lever 212 remains in the position shown by Fig. 41. Upon releasing the treadle 200, the spring 208 projects the movable stop member toward the stationary 15 member so far as to cause the ear 210 to engage the rear side of the retaining arm 211 at which position the sleeve 207 and the movable stop member are held so long as the ear is engaged by the retaining arm. When 20 the speed of the shaft 20 becomes so slow as to be insufficient to prevail over the tension of the spring 215, the weighted lever 212 is retracted to its normal position thus disengaging the ear 210 and permitting the 25 spring 208 to project the movable stop member against the end of the bearing 21. The shaft 20 may then continue to revolve only so far as to cause the stop finger 204 to engage the stop shoulder 203 whereupon all 30 movement of the shaft is arrested. The purpose of forming the stop finger 204 on a helical spring as shown is to provide a yielding cushion rather than an absolutely rigid device for absorbing the impact 35 caused by engaging the stationary stop member.

Having thus explained the nature of my said invention and described a way of constructing and using the same, although without attempting to set forth all of the forms in which it may be made or all of the modes 40 of its use, I declare that what I claim is:—

1. In a lock stitch sewing machine, a segmental shuttle race having a gap to admit a 45 loop of thread to the shuttle, a rotary shuttle having a segmental flange in coactive relation with said race and having a nose between the ends of said flange to enter the loop of thread, a shuttle-supporting member movable to and from engagement with the shuttle, said shuttle having a shoulder arranged to be engaged by and disengaged from said supporting member, and means 50 for causing said supporting member to operatively engage the shuttle while the nose of the shuttle is passing across the gap of the race.

2. In a lock stitch sewing machine, a rotary shuttle and a shuttle race arranged so 60 that their axes are substantially horizontal, said race having a gap at its lower side to admit a loop of thread, and said shuttle having a segmental race-engaging flange and a gap between the ends thereof, a shuttle-supporting member movable to and from en-

gagement with the shuttle, the shuttle having a shoulder adapted to coact with said supporting member, and means for causing said supporting member to operatively engage the shuttle while the space between the ends of the shuttle flange registers with the gap in the race. 70

3. In a lock stitch sewing machine, a rotary shuttle having a segmental external flange and a concentric cylindric surface of 75 relatively small diameter, a segmental shuttle race for supporting the shuttle by the flange thereof, said race having a gap to admit a loop of thread to the shuttle, and a member movable to and from engagement with the shuttle for holding the shuttle in concentric relation while the gap between the ends of said flange is in registering relation with the gap of the race, said movable member being adapted to coact with said 80 concentric surface of the shuttle. 85

4. In a machine of the character described, a revoluble shuttle formed with a peripheral gap and a shoulder within the marginal portion, a shuttle race formed with 90 a gap, a continuously revolving driver for the shuttle, and a member pivotally connected to and supported by the driver for engaging said shoulder to confine the shuttle centrally within the race, said member being 95 retractile to permit the passing of a loop of thread between it and the shuttle.

5. In a machine of the character described, a revoluble shuttle having an end wall formed with an aperture, a segmental 100 shuttle race supporting the shuttle by its periphery, the shuttle having a recess in its periphery, a rotary driver for the shuttle, a member pivotally mounted upon and movable with the driver for engaging the wall 105 of said aperture, and means for moving said member into and out of said aperture.

6. In a machine of the character described, a revoluble shuttle having an end wall formed with an aperture, a shuttle race, 110 a rotary driver for the shuttle, a member pivotally mounted upon the driver for engaging the wall of said aperture to support the shuttle, and means for oscillating said member into and out of said aperture. 115

7. In a lock-stitch sewing-machine, a circular shuttle race having a gap for the reception and discharge of the loop of needle thread, a rotating shuttle having a loop-pulling nose, the body of the shuttle having 120 a segmental guiding flange and said nose having a segmental guiding flange, a shuttle-supporting member movable to and from engagement with the shuttle, the shuttle having a surface for engaging said supporting 125 member, and means for actuating said supporting member so as to cause it to operatively engage the shuttle continuously from the time the rear end of the shuttle flange enters said gap in the race until said nose 130

flange has crossed the gap and again engaged the race, said actuating means being adapted to retract said supporting member from the shuttle to enable the loop of needle thread to pass.

8. In a machine of the character described, a rotatable shuttle, a shuttle race having a gap for the reception and discharge of the loop of needle thread, a shuttle driver, 10 a shuttle-supporting member movable to and from engagement with the shuttle, and means within the shuttle race for moving said supporting member to and from engagement with the shuttle.
- 15 9. In a machine of the character de-

scribed, a rotatable shuttle, a shuttle race having a gap for the reception and discharge of the loop of needle thread, a shuttle driver, a shuttle-supporting member carried rotatively by said driver, said supporting member being movable to and from engagement with the shuttle, and means in the shuttle race for moving said supporting member to and from engagement with the shuttle.

In testimony whereof I have affixed my 25 signature, in presence of two witnesses.
